UNITED STATES PATENT OFFICE.

WILLIAM TRACEY, OF DETROIT, MICHIGAN.

INTERNAL-COMBUSTION ENGINE.

Application filed November 22, 1926. Serial No. 149,941.

My invention relates to improvements in internal combustion engines of the compression type. An object is to provide such an internal combustion engine so constructed and arranged that the extent of the compression space within the combustion chamber or chambers may be varied at will and during the running of the engine.

More specifically, an object of my invention is the provision, in an internal combustion engine of the character described fitted with cylinders and working pistons, of mechanism cooperating with the pistons whereby they may be advanced or withdrawn during the running of the engine to vary the extent of the compression space in the several cylinders within which the pistons are mounted.

An important feature resides in the employment of a plurality of cylinders, each fitted with a working piston coupled with a transmission shaft to impart a rotary impulse thereto upon the power stroke of the piston and to travel freely thereover upon the return stroke and operating mechanism adapted to be actuated to advance or withdraw the pistons to vary the extent of the compression space in each of the several cylinders and operable to accomplish such result during the running of the engine.

The advantages of a high compression engine are at the present time minimized by the difficulty of starting the engine. My improved engine is so constructed that it may be started upon relatively low compression and the extent of the compression chamber reduced as desired during the running of the engine to increase the compression thereby obtaining all of the advantages of an engine of the high compression type in an engine employing low compression for starting.

Other objects and advantages of my invention and meritorious features of my construction will more fully appear from the following description of the embodiment shown in the accompanying drawings and defined in the claims.

In the drawings:

Fig. 1 is a vertical sectional view through an engine embodying my improvement.

Fig. 2 is a horizontal sectional view taken on the line 2—2 of Fig. 1.

Fig. 3 is a sectional view taken on the line 3—3 of Fig. 1. 55

Fig. 4 is a sectional view taken on line 4—4 of Fig. 2.

Fig. 5 is a sectional view taken on line 5—5 of Fig. 4.

Fig. 6 is a sectional view taken on line 6—6 of Fig. 1.

I have illustrated my improvement in a simple form of engine design comprising four aligned combustion chambers or cylinders 10. Each cylinder is provided with a 65 piston 12. Each piston is provided with a worm 14. The worm is adapted to serve the purpose of a rack, in a rack and pinion mechanism, during the reciprocation of the piston to drive a gear 16 mounted upon the 70 transmission shaft 18. A pair of transmission shafts 18 are provided arranged on opposite sides of the pistons so that the gears 16 are in mesh with the worms 14 of the several pistons. A plurality of gears or 75 pinions 20 are suitably supported between the several pistons, as illustrated in Figs. 1 and 2, engaged with the worms 14 of the pistons. One of these gears 20 is engaged with a rack 22 which is pivoted to a crank 80 24 which is in turn pivoted to a flywheel 26 that is supported as at 28 so as to drive the flywheel upon reciprocation of the pistons.

The pistons are of substantial length and 85 may be advanced or withdrawn during the running of the engine. The means for accomplishing this is here shown as embodied in a plurality of rotatable shafts 30, one for each piston, over which the piston is 90 telescopically arranged. The piston is keyed to the shaft as at 32 to rotate therewith but is capable of reciprocation over the shaft.

Each rotatable shaft carries a gear or pinion 34 keyed thereto as at 36. A shaft 95 38 is provided with worms 40 engaged with the gears 34 to rotate the shafts 30 and thereby the pistons upon rotation of the shaft 38, thereby advancing or withdrawing the pistons with respect to the gears 16 and 100 with respect to the cylinders 10 within which the pistons are mounted, thereby increasing or decreasing the compression space in each cylinder.

The gears 16 are so mounted upon the 105 transmission shafts 18 that such shafts are

picked up for rotation when such gears are rotating in one direction but travel freely over such shafts when rotating in the opposite direction.

- 5 I have here shown each gear as recessed on both sides to receive a pinion 42. These pinions 42 are pinned to the shafts 18 as at 44 to rotate therewith. Each pinion is provided with teeth 46 and each gear 16 is provided with a plurality of pawls 48 held by springs 50 to engage the teeth 46 of the pinions 42. Each pawl has a bearing in a recess 52 to seat therein to take the thrust when engaged with the pinion 42, and each 15 pawl is mounted upon a pivot 54 but the opening in the pawl is oversize the pin so as to permit the seat 52 in the gear 16 rather than the pivot pin 54 to receive the thrust of the pawl.
- 20 The teeth 46 in the gear 16 are so relatively arranged that one pawl, at least, will always seat fully against one tooth. This is obtained by such a relative variation in size of the teeth as to accomplish such result.

25 What I claim is:

1. In an internal combustion engine of the compression type, a plurality of cylinders each provided with a working piston, a worm carried by each piston, a pair of power transmission shafts arranged on opposite sides of the pistons, a plurality of gears on each shaft one for each piston and geared to the piston to be driven thereby, each gear coupled with the shaft upon which 30 it is mounted to rotate the shaft in one direction and to travel thereover when rotating in the opposite direction, a plurality of gears coupling the pistons together and to a flywheel to drive said flywheel, means coupled with the pistons to move them as a unit with respect to the cylinders to reduce or 35 increase the compression space in each cylinder.

2. In an internal combustion engine of the compression type, a plurality of cylinders each provided with a working piston, a worm carried by each piston, a pair of power transmission shafts arranged on opposite sides of the pistons, a plurality of 40 gears on each shaft one for each piston and geared to the piston to be driven thereby, each gear coupled with the shaft upon which it is mounted to rotate the shaft in one direction and to travel thereover when rotating in the opposite direction, a plurality of 45 gears coupling the pistons together and to a flywheel to drive said flywheel, a gear coupled with each piston, a worm engaging said gears to rotate them to move the pistons with respect to the gears on the transmission shafts and with respect to the cylinders within which the pistons are mounted to reduce or increase the compression space in each piston.

- 65 3. In an internal combustion engine of

the compression type, a plurality of aligned cylinders, a working piston mounted in each cylinder, a worm carried by each piston, a pair of power transmission shafts mounted on opposite sides of the pistons, a plurality of gears loosely mounted upon each shaft one for each piston, each gear engaged with the worm of the corresponding piston to be rotated thereby upon reciprocation of the piston, means coupled with each gear to automatically pick up the shaft upon which the gear is mounted to rotate the same upon rotation of the gear in one direction only adapted to permit the gear to travel freely over the shaft when rotating in the opposite direction, a plurality of gears coupling the pistons together and to a flywheel to drive said flywheel, a gear coupled with each piston, a worm shaft engaged with said last named gears operable to rotate the pistons to move them with respect to the cylinders within which they are mounted to reduce or increase the compression space in each cylinder.

4. In an internal combustion engine of the compression type, a plurality of cylinders, a working piston in each cylinder, a worm on each piston, a power transmission shaft, a plurality of gears on the shaft one engaged with each piston worm to be rotated thereby upon reciprocation of the piston, means coupling each gear with the shaft upon which it is mounted to rotate the shaft when the gear is rotating in one direction and to travel over the shaft when the gear is rotating in the opposite direction, a flywheel, means coupling the pistons with the flywheel to rotate the same, means coupled with the pistons to raise or lower them with respect to the cylinders within which they are mounted to decrease or increase the compression space in the several cylinders equally.

5. In an internal combustion engine of the compression type, a plurality of cylinders, a working piston within each cylinder, a worm on each piston, a pair of power transmission shafts one on each side of the pistons, means on each shaft engaging the worm of each piston to receive a power impulse therefrom to rotate the shaft in one direction only, a flywheel coupled with the several pistons to be driven thereby, and means operable to move the pistons as a unit to vary equally the size of the compression spaces within the several cylinders.

6. In an internal combustion engine of the compression type, a plurality of cylinders, a working piston in each cylinder, a worm on each piston, a pair of power transmission shafts arranged on opposite sides of the pistons, a plurality of gears mounted upon each shaft one for each piston and engaged with the worm thereon to be rotated thereby upon reciprocation of the piston,

- each gear coupled with the shaft upon which it is mounted to pick up the shaft for rotation upon rotation of the gear in one direction only and adapted to travel over the shaft when rotating in the opposite direction, means engaging each piston to move the same with respect to the cylinder and the transmission shaft to vary the compression space within the cylinder.
10. 7. In an internal combustion engine of the compression type, a plurality of cylinders, a working piston in each cylinder, a worm on each piston, a pair of power transmission shafts arranged on opposite sides of the pistons, a plurality of gears mounted upon each shaft one for each piston and engaged with the worm thereon to be rotated thereby upon reciprocation of the piston, each gear coupled with the shaft upon which it is mounted to pick up the shaft for rotation upon rotation of the gear in one direction only and adapted to travel over the shaft when rotating in the opposite direction, a rotatable shaft keyed to each piston to rotate therewith while permitting the piston to reciprocate thereover, and means engaging the several rotatable shafts last named to actuate them to advance or withdraw the pistons with respect to the gears on the power transmission shafts to reduce or increase the compression spaces in the several cylinders.
8. In an internal combustion engine of the compression type, a plurality of cylinders, a working piston in each cylinder, a worm on each piston, a pair of power transmission shafts arranged on opposite sides of the pistons, a plurality of gears mounted upon each shaft one for each piston and engaged with the worm thereon to be rotated thereby upon reciprocation of the piston, each gear coupled with the shaft upon which it is mounted to pick up the shaft for rotation upon rotation of the gear in one direction only and adapted to travel over the shaft when rotating in the opposite direction and means engaging the pistons to advance or withdraw them as a unit with respect to the cylinders to reduce or increase the compression chamber spaces in the cylinders.
50. 9. In an internal combustion engine of the compression type, a plurality of cylinders, a working piston in each cylinder, a worm on each piston, a pair of power transmission shafts arranged on opposite sides of the pistons, a plurality of gears mounted upon each shaft one for each piston and engaged with the worm thereon to be rotated thereby upon reciprocation of the piston, each gear coupled with the shaft upon which it is mounted to pick up the shaft for rotation upon rotation of the gear in one direction only and adapted to travel over the shaft when rotating in the opposite direction, said pistons adapted to be advanced or withdrawn to overrun the gears on the transmission shafts to reduce or increase the compression space in each of the several cylinders.
10. In an internal combustion engine of the compression type, a plurality of cylinders, a working piston in each cylinder, a worm on each piston, a pair of power transmission shafts arranged on opposite sides of the pistons, a plurality of gears mounted upon each shaft one for each piston and engaged with the worm thereon to be rotated thereby upon reciprocation of the piston, each gear coupled with the shaft upon which it is mounted to pick up the shaft for rotation upon rotation of the gear in one direction only and adapted to travel over the shaft when rotating in the opposite direction, each piston so coupled with its gear on the transmission shaft as to permit the piston to be advanced or withdrawn thereover during rotation of the gear to increase or decrease the compression space in the cylinder within which the piston is mounted.
11. In an internal combustion engine of the compression type, a cylinder, a reciprocating piston therein, means coupled with the piston to receive a power impulse therefrom, said piston being rotatable with respect to the means coupled therewith to receive the power impulse therefrom and means engaging the piston to rotate the same to vary the compression space within the cylinder.
12. In an internal combustion engine of the compression type, a cylinder, a working piston therein, a rotatable member coupled with the piston to be driven by the reciprocation thereof, said piston so coupled with the rotatable member as to be capable of rotation with respect thereto and with respect to the cylinder to vary the extent of the compression space within the cylinder, and means extending axially into the piston and coupled therewith to rotate the piston to travel thereover.
13. In an internal combustion engine of the compression type, a cylinder, a working piston therein, a rotatable member coupled with the piston to be driven by the reciprocation thereof, said piston coupled with the rotatable member as to be capable of rotation with respect thereto during the reciprocation of the piston and the rotation of the rotatable member to vary the extent of the compression space within the cylinder and mechanism comprising a rotatable shaft disposed axially within the piston and coupled therewith to rotate the piston to travel thereover and means engaging said shaft to rotate the same.
14. In an internal combustion engine of the compression type, a plurality of aligned cylinders, a working piston in each cylinder, a pair of power transmission shafts arranged on opposite sides of the pistons, each piston provided with a worm, each power

- transmission shaft provided with a plurality of gears loosely mounted thereon and engaged with the worms of the pistons to be rotated upon reciprocation of the pistons, 5 a clutch device for each gear automatically operable to pick up the transmission shaft to rotate therewith when the gear is being rotated in one direction but adapted to permit the gears to run over the shaft when 10 rotated in the opposite direction, a rotatable shaft telescopically arranged within each piston and keyed thereto to rotate therewith while permitting the pistons to reciprocate thereover, means engaging each of said rotatable shafts to rotate them in unison to 15 rotate the pistons to be advanced or withdrawn with respect to the gears on the transmission shaft to reduce or increase the compression spaces in the several cylinders 20 equally, a flywheel, a plurality of gears arranged between the several pistons engaged with the worms thereof and coupled with the flywheel to drive the same upon reciprocation of the pistons.
- 25 15. In an internal combustion engine of the compression type, a cylinder, a working piston therein having a power transmitting extension held to travel in a straight line, a rotatable member coupled with said extension to receive a power impulse therefrom and means engaging said extension to rotate the piston to actuate the same linearly with respect to said rotatable member and with respect to the cylinder.
- 30 16. An internal combustion engine of the compression type having a plurality of cylinders, a reciprocating piston in each cylinder provided with a tubular power transmitting extension, a rotatable member coupled 35 with said extension to receive power impulses therefrom, a rotatable shaft positioned within said tubular extension and coupled therewith to rotate the same while permitting travel of the piston thereover,
- means engaging said shaft for rotation, said piston adapted upon rotation of the shaft to be actuated to travel linearly thereover. 45
17. An internal combustion engine of the compression type having a plurality of cylinders, a working piston in each cylinder having a tubular extension provided with a worm, a worm gear engaging such extension to receive a power impulse therefrom, a rotatable shaft disposed within said extension and coupled thereto to rotate the piston to travel over the shaft, means engaging said shaft to rotate the shaft, a flywheel coupled through a train of gears arranged between the worm extensions of said pistons to be driven therefrom. 50
18. An internal combustion engine of the compression type having a plurality of cylinders arranged in line, a piston for each cylinder provided with a tubular worm extension held to travel in a straight line; a train of gears, one for each worm extension, arranged between the worm extensions of the pistons coupling said pistons together and with a rotatable member to rotate said member, and a rotatable shaft disposed within the tubular worm extension of each piston and coupled therewith to rotate the same to travel longitudinally thereover. 55
19. An internal combustion engine of the compression type having a plurality of cylinders, a working piston for each cylinder provided with a tubular worm extension mounted upon a rotatable shaft and coupled with the shaft to rotate therewith and capable of travel longitudinally thereover, means for rotating said shaft, a flywheel coupled through a train of gears arranged between the worm extensions of said piston and enmeshed therewith to receive a power impulse from each piston. 60

In testimony whereof, I, WILLIAM TRACEY, sign this specification.

WILLIAM TRACEY.
